UNITED STATES PATENT OFFICE.

HARRY EBERT, OF FREDERICK, MARYLAND.

BAG-CLOSURE.

1,071,991.

Specification of Letters Patent.

Patented Sept. 2, 1913.

Application filed August 9, 1912. Serial No. 714,209.

To all whom it may concern:

Be it known that I, HARRY EBERT, a citizen of the United States, residing at Frederick, in the county of Frederick and State 5 of Maryland, have invented new and useful Improvements in Bag-Closures, of which the following is a specification.

This invention relates to bag closures, more especially to closures for mail bags or 10 pouches and is an improvement on that type of closures which fasten the open end of the bag or pouch flatwise by means of a cover or top movable longitudinally over the contacting sides of the bag in guide 15 channels provided therefor at the mouth of the bag or pouch.

The object of the invention is to provide a closure of this character which shall be simple and cheap, and which may be quickly 20 slipped into and from its place over the mouth of the bag or pouch and which cannot become detached and lost; and to this end the invention consists of the novel construction and combination of parts herein- 25 after described in detail and set forth in the appended claims, reference being had to the accompanying drawings in which—

Figure 1 is a side elevation of the mouth of a mail bag or pouch closed. Fig. 2 is a 30 similar view with the closure opened to its fullest extent. Fig. 3 is an enlarged view looking down upon the mouth of the bag with the closure omitted and the central portion of the bag or pouch broken away. Fig. 4 is a sectional view on the plane of the line 4—4, Fig. 2, of so much of the bag or pouch as is shown in Fig. 3. Fig. 5 is a 35 vertical cross-sectional view of the mouth of a mail bag or pouch and its closure on the line 5—5 of Fig. 1, the closure being separated from the bag or pouch to more clearly illustrate the parts. Fig. 6 is a side elevation of a modified form of the invention. Fig. 7 is an enlarged sectional view on the 40 line 7—7 of Fig. 6, the central portion of the bag or pouch being broken away and the closure omitted. Fig. 8 is a sectional view on the line 8—8 of Fig. 7 with the closure in its retracted position. Fig. 9 is 45 a cross-sectional view on the line 9—9 of Fig. 7. Fig. 10 is an enlarged detailed side view of a modified form of the bag or pouch showing the construction of certain parts.

50 In the drawings 10 designates the bag or pouch of canvas, leather or other suitable

material, having at one end an open mouth normally long and narrow but which may be opened to a greater extent when necessary to fill or empty the bag or pouch.

Surrounding the mouth of the bag or pouch 10 is a band or welt 11 of leather or other suitable material in one or more layers, two being shown in the drawings. The 55 layers of the welt 11 are secured upon the outer side of the bag around the same by rows of stitching 12, and rivets 13, other means, however, may be employed for securing the welt to the bag if desired. Below the welt 11 and spaced a short distance 60 therefrom is a second encircling band 14 wider than the welt which may also be made of two or more layers of leather the outermost layer 15 being wider than the others and extending nearly to the welt 11 so as 65 to form a channel 16 between the welt and the band 14 on each side of the bag, see Figs. 4 and 5. The band 14 may be secured to the bag or pouch 10 in any desired manner, but is here shown as fastened by a row 70 of stitching 17 near its bottom edge, and by a number of closely spaced large headed rivets 18 the heads of which extend as high as the top edge of the outermost layer 15 of the band 14 and serve to give a firm 75 rigid support to said layer and prevent that portion of it in front of the channel 16 from being bent or turned outward.

The inside of the bag or pouch around the mouth is reinforced by a number of spaced 80 plates 19, preferably of metal, held in place by the aforesaid rivets 13 and 18 and by other rivets 20 each of which passes through the bottom of the plates and the band 14. The plates 19 serve to hold the welt 11 properly 85 spaced from the band 14 and prevent the channel 16 from collapsing when it is empty.

The mouth of the bag or pouch 10 is elongated as heretofore stated with rounded ends 100 and straight sides close together as clearly shown in Figs. 3 and 4 and provided with a sliding closure 21 in the form of a cap made with a crown 22 of canvas or leather and a rim 23 of some stiff material, preferably 105 leather, stitched or otherwise fastened on the margin of the two sides and one end of the crown, the rim at the sides of the closure being of a size to fit snugly and adapted to slide smoothly within the 110 channel 16 at the mouth of the bag. The crown 22 when the closure is in place covers

the mouth of the bag and overlies the welt 11, passing through a narrow slot 24 on each side of the bag between the welt and the outer layer 15 of the band 14. At its 5 rear end the rim 23 of the cap is curved to fit snugly in the curved portion *a* of the channel 16 when the bag is closed. The rim 23 is omitted from the forward end of the closure 21, the crown being formed into a 10 flap tab 25 bound with leather and provided with a slot to fit over a staple 26 projecting from the band 14 at one end of the mouth to which a suitable lock 27 and label holder 28 are applied in the usual manner. At the 15 forward end of the closure where the rim 23 terminates there is fastened a transverse strip 29 that abuts at its ends, when the closure is opened, against two stops 30 which project upward over the rim 14 near the 20 open portion *a* of the channel 16 and prevent the closure from being entirely withdrawn from the bag or pouch 10. When the lock 27 and the label holder 28 are removed from the staple 26 and the tab 25 25 also disconnected from the same, the bag is readily opened by grasping a loop 31 on the rear of the closure and pulling the same endwise into the position indicated in Fig. 2. In this position the mouth of the bag 30 is fully opened and ready to be filled or emptied.

Instead of forming the outer layer 15 of the band 14 of leather and stiffening it by large headed rivets 18, this outer layer may 35 be made as at 35, Figs. 6 to 10, of a strip of canvas 36 doubled upon itself and enfolding therein a number of metal plates 37 alternating with a number of leather strips 38, being respectively riveted and sewed to the 40 band 14 and the bag 10, as shown most clearly in Figs. 9 and 10. Instead of retaining the closure on the bag by means of the transverse strip 29 and stops 30, a cord 39 attached at its ends to the ends of the 45 closure 21 and passing freely through an opening 40 in the welt 11 retains the closure in its place on the bag and permits it to move freely in the channels 16.

What I claim is:—

50 1. A bag or pouch having an open mouth, an exterior marginal welt around the mouth, a band surrounding the bag or pouch below the welt and spaced therefrom, a strip secured on the outer side of the band on each 55 side of the bag and extending above the same close to the welt, said welt, band and strip together forming a channel nearly closed on each side of the bag, and a closure having side rims fitting said channels and 60 slidale therein to permit the closure moving endwise over the bag or pouch.

65 2. A bag or pouch having an open mouth, an exterior marginal welt around the mouth, a band surrounding the bag or pouch below the welt and spaced therefrom to form a

channel, a strip over the band at the sides of the bag extending above the band and close to the welt to nearly inclose said channel, reinforcing means for preventing the strip from being bent outwardly, and a 70 closure having side rims fitting said channels and slidale therein to permit the closure moving endwise over the bag mouth.

3. A bag or pouch having an open mouth, an exterior marginal welt around the mouth, 75 a band surrounding the bag or pouch below the welt and spaced therefrom to form a channel, a strip over the band at the sides of the bag extending above the band and close to the welt to nearly inclose said channel, a plurality of reinforcing metal strips within the mouth of the bag, a plurality of rivets extending through the band to the reinforcing plates within the bag and having large heads the margins of which extend to 80 the top of the strip on the outer side of said band, and a closure having side rims fitting said channels and slidale therein to permit the closure moving endwise over the bag mouth.

4. A bag or pouch having an open mouth, an exterior marginal welt around the mouth, a band surrounding the bag or pouch below the welt and spaced therefrom to form a channel, a strip around the band extending 85 above the same and close to the welt to nearly inclose said channel, a space being left between the strip and the welt, reinforcing means for preventing the strip being bent outwardly, and a closure comprising 90 100 a cap with side rims fitting said channels and slidale therein to permit the closure moving endwise over the bag mouth, said cap running freely through the space between the strip and the welt as the closure 105 is moved to open and close the bag.

5. A bag or pouch having an open mouth, and an exterior marginal welt around the mouth, a band surrounding the bag or pouch below the welt and spaced therefrom to 110 form a channel, a strip around the band extending above the same and close to the welt to nearly inclose said channel, spaced reinforcing means on the exterior of said strip for preventing the same being bent 115 outwardly, a closure having side rims fitting said channels and slidale therein to permit the closure moving endwise over the bag mouth, and means carried by said closure for preventing its withdrawal over the bag. 120

6. A bag or pouch having an open mouth, an exterior marginal welt around the mouth, a band surrounding the bag or pouch below the welt and spaced therefrom to form a channel, a strip around the band extending 125 above the same and close to the welt to nearly inclose said channel, spaced reinforcing means on the exterior of said strip for preventing the same being bent outwardly, a closure having side rims fitting 130

said channels and slidale therein to permit the closure moving endwise over the bag mouth, stops on the rear end of the mouth of the bag, and means carried by the forward end of the closure to abut against said stops and prevent withdrawal of the closure from the bag.

In testimony whereof I have hereunto set my hand in presence of two subscribing witnesses.

HARRY EBERT.
